JAMES P. BRIDGE, OF BOSTON, MASSACHUSETTS.

Letters Patent No. 86,808, dated February 9, 1869.

IMPROVED COMPOUND FOR PRESERVING WOOD, LEATHER, &c.

The Schedule referred to in these Letters Patent and making part of the same.

To all whom it may concern:

Be it known that I, JAMES P. BRIDGE, of Boston, in the county of Suffolk, and State of Massachusetts, have invented a new and improved Compound for Preserving Wood and Leather, and Rendering Wood Non-Combustible; and I do hereby declare that the following is a full, clear, and exact description thereof, which will enable those skilled in the art to make and use the same.

After the wood or leather has been subjected to a sufficient degree of heat or superheated steam to evaporate all moisture therefrom, it is to be subjected to a bath of vaporized sulphate of ammonia, to render the wood non-combustible. This vapor, penetrating into and saturating the pores of the wood, not only renders it non-combustible, but also acts as a powerful preservative of the wood, which is previously subjected to the action of a hydrocarbon-vapor, formed from heated rosin mixed with salt, which, by actual experiment and

many tests, has been ascertained to be an excellent preservative of both wood and leather.

I am aware that wood and leather have been subjected to the action of oleaginous vapors for purposes of preservation; but

What I claim as my invention, and desire to secure by Letters Patent, is—

The preservation of wood and leather by the action of a hydrocarbon-vapor, formed from rosin and salt, substantially as set forth.

Also, subjecting wood to the action of vaporized sulphate of ammonia, for the purpose of preservation and rendering it non-combustible, substantially as set forth.

JAS. P. BRIDGE.
